UNITED STATES PATENT OFFICE

ERNST UDET, OF BERLIN, GERMANY

MOVING TARGET FOR PRACTICE SHOOTING

Application filed March 26, 1930, Serial No. 438,983, and in Germany December 9, 1929.

This invention relates to practice shooting and particularly to moving silhouettes simulating aircraft as targets for practice shooting.

5 The invention fills a much needed want in antiaircraft practice shooting, as heretofore no targets were known which were comparable in shape and movement with aircraft and could be used without danger to the towing aircraft.

Further according to my invention a sheet is used in the form of a triangle having unequal sides, with the base attached to the cable and the longer side at the top. The tip or apex of the triangle is preferably rounded. This shape has the advantage that the sheet remains taut at all angles which the cable normally assumes when diverging from the vertical position owing to changes of speed 10 of the aircraft, changes of length of the cable, different loads on the cable and so on.

The invention is illustrated in the annexed drawings. Fig. 1 shows a towing aeroplane with a silhouette target representing an aeroplane in side elevation. Figs. 2 to 4 show targets representing aeroplanes in perspective.

1 designates a towing aircraft, from the fuselage of which depends a long cable 2 adapted to be hauled in and payed out. 3 is a weight or loading attached to the lower end of the cable for holding it in a substantially vertical position. 4 designates a sheet preferably of fine mesh gauze, to which is attached a silhouette 5 of an aircraft, formed of black silk or the like. White lines on the silhouette indicate the position of the important parts to aim at, for instance, the fuel tank 7, the pilot 8, the gun position 9 and the machine-gunner 10.

The transparent fabric 4 may be secured to the cable 2 in any suitable manner. One edge thereof is attached to the cable 2 throughout the edge length. The cable is hauled into the plane for the first time when the plane is still standing on the ground and during the hauling in step the fabric is retained behind the cable 2, so that when the cable is payed out from the plane in flight the fabric surface is instantly seized by the air current and

stretched backwards tightly. When the cable is hauled in during flight the fabric surface is caused in an entirely natural manner to lie behind the cable in a suitably folded position for the next hauling out operation. During the initial hauling in step, while the plane is on the ground, the doubling up or folding of the fabric in a zigzag fashion behind the cable looking in the direction of flight facilitates the first hauling out operation.

Figs. 2 to 4 show silhouettes representing banking, diving or turning aeroplanes, so that the gunner practising may also be offered these positions as a target.

The towing aeroplane 1 is at a considerable height above the towed target, so that the practising gunner is not liable to hit it, even when shooting inaccurately. The shots do little damage to the silk and gauze. The area of the gauze is, preferably, greater than that of the silhouette, so that within certain limits the mis-shots will also be registered on the target.

The method of towing enables the normal flying movements, such as climbing, diving and turning, to be faithfully reproduced.

Of course the targets may also represent air ships and the like.

What I claim is:

1. Means for target practice comprising a motor-driven aircraft, a cable carried by the said aircraft, the said cable being adapted to be payed out and hauled in, a transparent fabric attached to the cable along one edge and adapted to be readily folded behind the cable, said fabric bearing a silhouette of a flying machine and the like forming a moving target for practice shooting, and a loading provided on the free end of the cable and adapted to hold the cable in a substantially vertical position, the fabric being adapted to be unfolded by the air current when the cable is payed out from the aircraft and to be held taut in the air.

2. The combination according to claim 1 with the silhouette representing the flying machine in curve position.

3. Means for target practice comprising a motor-driven aircraft, a cable carried by the said aircraft, the said cable being adapted to

be payed out and hauled in and carrying a transparent fabric, said fabric bearing a silhouette simulating an object forming a moving target for target practice, and a weight provided on the free end of the cable and adapted to hold the cable in a substantially vertical position, the fabric being adapted to be unfolded by the air current when the cable is payed out from the aircraft and to be held taut in the air, with transparent lines on the silhouette indicating the position of important parts of the target to aim at.

- 10 4. Means for target practice comprising a motor-driven aircraft, a cable carried by the said aircraft, the said cable being adapted to be payed out and hauled in and carrying a transparent fabric, said fabric bearing a silhouette simulating an object forming a moving target for target practice, and a weight provided on the free end of the cable and adapted to hold the cable in a substantially vertical position, the fabric being adapted to be unfolded by the air current when the cable is payed out from the aircraft and to be held taut in the air, the silhouette being surrounded by a broad margin of the transparent material adapted to serve as indicator for shots that have missed the mark.
- 15 5. Means for target practice comprising a motor-driven aircraft, a cable carried by the said aircraft, the said cable being adapted to be payed out and hauled in and carrying a transparent fabric, said fabric bearing a silhouette simulating an object forming a moving target for target practice, and a weight provided on the free end of the cable and adapted to hold the cable in a substantially vertical position, the fabric being adapted to be unfolded by the air current when the cable is payed out from the aircraft and to be held taut in the air, with the silhouette representing an aircraft in oblique position.

- 20 6. A target for target practice consisting of a transparent sheet of foldable fabric having an opaque silhouette of fabric in the form and size of an airplane simulated and adapted to be fastened to a cable and to be towed in a substantially vertical plane through the air by means of an aircraft carrying said cable, the silhouette being formed with transparent parts indicating vulnerable points of the target.

In testimony whereof, I have signed my name to this specification.

55 ERNST UDET.
